LOUD SPEAKER

Adolph A. Thomas, New York, N. Y.

Application June 30, 1926. Serial No. 119,575

23 Claims. (CL 181—31)

My invention relates to sound-reproducing apparatus, and its object is to provide a loudspeaker of combined horn and cone type, so that the advantages of both may be realized in 5 a single instrument of compact construction.

It is generally recognized by acoustic engineers, particularly in the radio field, that a loudspeaker with a single diaphragm cannot reproduce the entire musical scale with proper tonal 10 value. That is true of the small diaphragms in horn speakers and the large diaphragms in cone speakers. It seems to be the prevailing opinion that the first type of loudspeaker gives a better 15 reproduction of the higher register, and that cone speakers favor the lower register.

In accordance with my invention I produce a 20 loudspeaker having a plurality of diaphragms arranged to be simultaneously operated by electromagnetic mechanism. At the present time I prefer to use three diaphragms designed to respond to all notes of the musical scale with substantially equal fidelity and uniform intensity. At least one of these diaphragms is of the cone 25 type that requires no horn for amplification. When I employ three diaphragms, the other two are connected with an amplifying horn. These two diaphragms are of different acoustic properties, one operating best on the high register, 30 and the other being most efficient on the middle register. The large cone diaphragm reproduces best the lower frequencies, particularly the deep bass notes. I may, however, use only one horn diaphragm.

All diaphragms in my combined horn and cone 35 speaker are simultaneously actuated by the same mechanism. In a preferred embodiment of my invention, a single armature of novel construction operates all three diaphragms, and the connections between those parts are so simple that 40 there is practically no lost motion. The two horn diaphragms are arranged at right angles to the cone diaphragm and communicate with the horn through a pair of lateral tone arms between 45 which the cone is mounted. The resultant structure is one of unusual compactness, permitting a large cone diaphragm and a horn of considerable length to be housed in a cabinet of comparatively small dimensions.

When I use only one horn diaphragm in combination with a cone, I provide a horn structure coiled upon itself to furnish an amplifying conduit of requisite length, and the cone is mounted 50 within the turns of the horn in a plane at right angles thereto. In this embodiment I prefer to

employ an improved form of electromagnetic mechanism designed to operate the two diaphragms simultaneously but slightly out of phase with each other. The acoustic result is a fuller and richer reproduction than if the diaphragms 60 vibrated in strict unison.

The foregoing and other features and advantages of my invention will be better understood from a detailed description of several embodiments shown by way of example in the accompanying drawings, where—

Fig. 1 shows in face view a combined horn and cone speaker constructed in accordance with my invention, the front of the enclosing cabinet being open to show the parts within;

Fig. 2 represents a transverse cross-section approximately on line 2—2 of Fig. 1;

Fig. 3 is a vertical cross-section on line 3—3 of Fig. 1, except that parts of the horn are shown 75 in full for clearness;

Fig. 4 is a rear view partly in section taken approximately on the broken line 4—4 of Fig. 3;

Fig. 5 is a detached view on an exaggerated scale showing certain structural details of the 80 magnet and armature for operating the two horn diaphragms and the cone diaphragm;

Fig. 6 is a side view of the magnetic structure shown in Fig. 5;

Fig. 7 is a cross-sectional detail on line 7—7 of Fig. 6, showing the mounting of one of the 85 magnet coils;

Fig. 8 is a detached perspective view on an enlarged scale, showing the construction and relative arrangement of the magnetic pole pieces and the bell-crank armature;

Fig. 9 shows a modification in which only one horn diaphragm is used, certain parts being shown in cross-section for clearness;

Fig. 10 is a detached view in cross-section showing the polar construction of the actuating magnet and the mounting of the controlling coils by which the two diaphragms are simultaneously operated;

Fig. 11 is a cross-section on line 11—11 of Fig. 10;

Fig. 12 shows a face view of a preferred form of diaphragm used in the construction of Fig. 9; and

Fig. 13 is a cross-section on line 13—13 of Fig. 12;

Before describing the figures in detail, I want to explain that I have intentionally illustrated certain parts in exaggerated proportion, particularly the electromagnetic actuating mechanism, for the purpose of making the drawings as clear

as possible. It will, therefore, be understood that the drawings are not to be taken as accurate shop drawings, but rather as pictorial illustrations of several embodiments of my invention. I shall 5 first describe the three-diaphragm speaker shown in Figs. 1-8.

The various parts that constitute the loud-speaker are housed in a casing or cabinet indicated as a whole by C. This cabinet may be of 10 any suitable construction and design, depending upon the size of the horn and cone diaphragm. In the present instance, I have shown a cabinet comprising a base 10, sides 11 and a back 12. The upper part of the cabinet may be arched, as 15 shown at 13, and provided at the front with a frame 14 adapted to receive the mouth of the horn, as will presently be made clear. It goes without saying that the cabinet as a whole is designed and finished as a beautiful piece of 20 household furniture in which all mechanism is concealed from view.

Within the cabinet is mounted a sound-amplifying horn indicated as a whole by H. This horn is so constructed as to provide a maximum 25 length of sound passage in a minimum space. To this end, the horn comprises a rear section 15, a front section 16, and an inner section consisting of a pair of lateral branch tubes 17 and 18. As seen in Fig. 2, these branch tubes are substantially U-shaped, terminating in inner arms 17' and 18' respectively. The branch tubes 17 and 18 form a Y-connection with the front horn section 16 as shown in Fig. 1. The rear section 15 of horn H extends upwardly along the back wall 30 of the cabinet and then curves forwardly until it terminates in a bell-shaped mouth 19, which fits into the correspondingly shaped frame 14 at the front of the cabinet. If desired, the outer edge of mouth 19 may be surrounded by a ring of felt 35 or other sound-deadening material. In the practical construction of the horn, it is convenient to make sections 15 and 16 separate and unite them by a suitable tight-fitting joint 20. The parts 40 16, 17 and 18 of the horn may be cast or molded as a single member, which is rigidly secured in the cabinet by any practical means. In the drawings I have shown the front section 16 resting on the recessed block 21, to which it is firmly 45 secured by a strap 22 fastened to the base of the cabinet. The block 21 is preferably of wood or other material which does not transmit acoustic vibrations, and a ring 23 of felt or like material may be interposed between strap 22 and horn section 16. The branch tubes 17 and 18 are secured 50 to the sides 11 of the cabinet by straps 24, which hold these tubes against recessed blocks 25. The rear section 15 of the horn is secured to the back wall 12 of casing C by a strap 26, which holds the horn against a block 27, as 55 previously described in reference to block 21 and horn section 16.

It will thus be seen that the horn H is rigidly supported within the cabinet and is acoustically insulated from its walls. The horn sections are 60 so shaped that they constitute a sound passage of progressively increasing cross-sectional area from the inner end of arms 17' and 18' to the mouth 19. This sound passage is of sufficient length to give the proper amplification of sound 65 waves entering the inner end of the horn. Owing to the construction of the horn, this long amplifying sound passage is completely enclosed in a cabinet of comparatively small dimensions, as will readily be appreciated by an inspection of 70 Figs. 1-4. The horn may be built of metallic

or non-metallic material suitable for acoustic purposes, as those familiar with the art will understand. If found necessary or desirable, the inner arms 17' and 18' may be steadied against vibration by a pair of brackets secured to the 80 walls of the casing, as diagrammatically indicated by dotted lines 28 in Fig. 4.

Within the cabinet is rigidly secured a supporting frame indicated as a whole by F. This frame may conveniently be cast or molded as a single member of suitable metal, such as aluminum, and it consists of a ring 29 supported on a pair of legs 30 which are firmly fastened to the base of the casing by screws 31 or otherwise. The ring 29 may be provided with integral radial arms 29' to increase the rigidity of the frame. A cone diaphragm D is secured at its edge to ring 29, as by means of a clamping ring 32, secured by screws 33, or in any other practical way. Diaphragm D may be constructed of any material suitable for acoustic purposes, such as moisture-proof paper, parchment, sheet metal and the like. Although I have shown the diaphragm circular, it may be of any other design capable of giving proper acoustic response. For instance, such 90 diaphragms can be given various forms of elliptical shapes. It will be noticed that the legs 30 of supporting frame F straddle the U-shaped portion 15-16 of the horn, so that the cone diaphragm is mounted between curved portions 105 of the horn. In the particular construction shown in Figs. 1-4, the diaphragm D is supported in the space between the lateral tubes 17 and 18, and between the upper and lower turns of the horn. Thus, it is seen that the diaphragm and its support do not demand any more 110 space than the horn itself requires, thereby producing a construction of great compactness that may be housed in a cabinet just big enough to enclose the horn.

The amplifying horn H is connected at its two inner ends with a pair of diaphragms 34 and 35. Diaphragm 34 communicates with tone arm 17' and diaphragm 35 is similarly connected with tone arm 18'. In order to facilitate assembling 120 of the diaphragms on their respective tone arms, I mount the diaphragms on a frame or casting indicated as a whole by E, which consists of a pair of rings 36 and 37 connected by arms 38. Diaphragm 34 is seated on ring 36 and is rigidly 125 held in position by a chambered disk or shallow casing 39 having a tubular extension 40 adapted to fit tight into the free end of tone arm 17'. Likewise, diaphragm 35 is secured on ring 37 by a chambered disk or shallow casing 41, which is 130 provided with a tubular extension 42 adapted to fit snugly into the free end of tone arm 18'. The disks or casings 39 and 41 are secured to the adjacent rings of frame E by screws 43 or other suitable fastening means. The tubular extensions 40 and 42 are adapted to be axially adjusted in their respective tone arms and they are secured in adjusted position by set-screws 44 or otherwise. In assembling this part of the mechanism, the tubular extensions 40 and 42 are first 140 inserted in their respective tone arms and then the framework E carrying the two diaphragms is inserted between the disks 39 and 41, which are then secured to the rings of frame E. The 145 slideable adjustment of the tubular extensions 40 and 41 permits the frame E to be adjusted in correct position with respect to the electromagnetic actuating mechanism, which presently will be described. After the disks 39 and 41 have been secured to frame E, and after the latter has been 150

axially adjusted into proper position, the set-screws 44 are tightened. If necessary, or desirable, tight-fitting thrust collars of metal may be inserted in the space 45 between the disks 39 and 51 and the annular edges 46 of tone arms 17' and 18'. This will be clear from Figs. 3 and 4 without additional illustration.

Diaphragms 34 and 35 are centrally connected by a rod 47 of sufficient rigidity to vibrate axially without buckling or otherwise deforming. It will be seen from Fig. 3 that diaphragm 34 is smaller than diaphragm 35. These two diaphragms are so designed and constructed that diaphragm 34 responds most effectively to the higher register of tones, while diaphragm 35 operates most efficiently in reproducing the middle register. The large diaphragm D, which requires no horn amplifier, tends to accentuate the lower register of the musical scale. So it will be understood that diaphragms 34, 35 and D, when simultaneously operated (as will presently be described), give a sound reproduction in which all tones of the musical scale are brought out with substantially uniform intensity, from the highest notes of the treble to the deepest notes of the bass. The correct design of the three diaphragms lies within the skill of the acoustic engineer and need not be dwelt upon here in detail. At this point I would call attention to the fact that tone arms 17' and 18' are of substantially equal length, so that the sound waves initiated by the diaphragms 34 and 35 will pass simultaneously into the front section 16 of the horn. By arranging these diaphragms in horizontal planes, as shown in Figs. 3 and 4, I secure a greater length of tone arm within the limited space available than if these diaphragms were arranged in parallel vertical planes directly in line with the points 48 of the tone arms (see Fig. 4). This suggested arrangement, however, is within the scope of my invention and will be understood without the need of additional illustration.

I now come to the electromagnetic mechanism for simultaneously operating the three diaphragms 34, 35 and D in accordance with current variations in a controlling circuit. There is a magnet M for maintaining a practically constant magnetic field of predetermined strength. This magnet may be of the permanent type, or it may be an electromagnet provided with one or more coils traversed by a substantially constant current of the requisite magnetizing strength. As best shown in Fig. 4, the supporting frame F is provided with a bracket or block 49, which may conveniently be formed integral with one of the cross-arms 29' of the frame. Screws 50 or other fastening means securely hold the magnet M in proper position on block 49. The construction of magnet M and the attached pole pieces is best illustrated in Figs. 5, 6 and 8, to which reference will now be had. The body of the magnet is bent laterally at 51 and terminates in an L-shaped polar extension 52. The other polar extension 53 is in line with the main body of the magnet and may be of rectangular shape, as shown in Fig. 5. The magnet is so designed that the polar terminals or extensions 52 and 53 have substantially the same cross-sectional area, so that the flux density through these extensions may be uniform. To the polar ends of magnet M are secured two L-shaped pole pieces 54 and 55 by means of screws 56 or other fastening devices. These screws are preferably of the same magnetic material as the magnet, so as to reduce the reluctance of the mag-

netic path. It will be seen from Fig. 5 that the L-shaped pole pieces 54 and 55 are secured to the magnet in symmetrical or balanced position, so that the magnetic field flux will divide evenly (or substantially so) between the two arms of each pole piece in passing from one magnet pole to the other. The dimensions of pole pieces 54 and 55 are so calculated that they are traversed by the magnetic flux below the point of saturation. It will be understood that the pole pieces 54 and 55 are made of magnetic material having a high permeability, such as soft steel and certain grades of iron which are well known to those skilled in the electrical art. Pole pieces 54 and 55 terminate at opposite ends in lateral lugs or extensions 57 and 58, which provide a pair of airgaps 59 and 60 of equal predetermined width. A bell-crank armature indicated as a whole by A is mounted on a bearing pin 61 in symmetrical relation to the pole pieces 54 and 55. In the present instance, the bearing pin 61 is carried by a non-magnetic block 62 which is firmly secured to pole piece 54 in the right-angled corner thereof (see Fig. 5). The bell-crank armature A, which is of soft steel or iron having high magnetic permeability, consists of a pair of right-angled arms 63 and 64. The normal position of the armature is such that the arms 63-64 extend centrally through airgaps 59-60. The rod 47, which connects diaphragms 34 and 35 as previously explained, passes through a screw-threaded hole 65 at the outer end of arm 64, and a pair of nuts 66 maintain the connection between rod 47 and arm 64 in rigid condition during the vibrations of the armature. The arm 63 of armature A is connected to the center of cone diaphragm D by a rod or other stiff connecting member 67, which is tightly held to arm 63 by a pair of nuts 68. Owing to the very small vibrations of the armature, the ends of arms 63 and 64 may be rigidly connected to the rods 47 and 67, respectively, even though the armature ends move in a slightly curved path. The rods 47 and 67 have sufficient resiliency or elasticity to take care of the slightly curved travel of the armature ends. By means of these rigid connections, all lost motion is eliminated, whereby the efficiency and sensitiveness of the instrument are increased. It is assumed, of course, that the supporting pivot 61 for the armature prevents loose play or lost motion of the armature at that point. The inherent resiliency of diaphragms 34, 35 and D normally holds the armature midway of the magnetic airgaps, as shown in Fig. 5, without the need of a separate centering and restoring spring.

The operation of armature A is controlled by a pair of coils 69 and 70, which are mounted on and between the right-angled arms of pole pieces 54 and 55. Clamps 71, preferably of non-magnetic spring metal, are secured to pole piece 54 (as by screws 72) and hold the coils firmly in position. The arms of the armature pass centrally through the coils. In Fig. 5 the coils are diagrammatically represented by dotted outlines, so as not to obscure the drawing. I may use a pair of non-magnetic plates 73 to hold the pole pieces 54 and 55 in properly spaced relation before attaching them to the magnet. The plates 73 may be of brass or aluminum, and they are connected to the pole pieces by screws or otherwise. In this way the pole pieces, the armature and the two magnetizing coils constitute a unit which is assembled before being secured to the magnet. The coils 69 and 70 are preferably connected in series so as to act like a single coil in a circuit of variable electric impulses. It will

not be necessary to show any circuit connections for the coils, because such circuits are well understood and do not form part of my present invention.

5 It will be seen from Fig. 5 that coils 69 and 70 are disposed symmetrically with respect to the right-angled armature A, whereby the magnetizing effect of the coils is uniformly distributed through the armature. It goes without 10 saying that the coils are so wound and connected that their magnetic effect at any instant is cumulative. That is to say, the two coils act like a single coil to polarize the armature in such a way that, when a north pole is formed at one 15 end, a south pole is formed at the other end of the armature. When the armature thus becomes polarized in a variable degree, the adjacent pole extensions 57 and 58 act upon the armature to produce vibration thereof in a manner well understood.

There remains to be described the modification shown in Figs. 9—13, in which only one diaphragm is used for the horn. In this construction, the amplifying horn H' consists of an 20 upper section 74, an intermediate U-shaped section 75, and an inner U-shaped section 76. These sections are properly fitted together at joints 77 and 78, so as to constitute a closed sound passage of progressively increasing cross-sectional 25 area. The horn is rigidly supported in upright position by clamps or straps 79, which may be similar to the straps 22 and 26 previously referred to. If found necessary or desirable, the 30 inner end of horn section 76 may be braced against vibrations by a suitable bracket 80, which has a pair of arms straddling the horn section 74 and secured to the back wall 12 of the casing. To the inner end of horn H' is secured 35 a shallow cylindrical casing 81 carrying a diaphragm 82. A frame F', which may be considered similar to frame F and therefore needs no further description, carries a cone diaphragm D' similar to diaphragm D. Diaphragm D' is provided at the center with a stiff rod 83 which carries at its free end an armature plate or bar 40 84.

As seen from Figs. 9 and 10, the diaphragm 82 and armature 84 are substantially parallel, and 45 between these two parts is arranged electromagnetic mechanism for simultaneously operating the diaphragms. This mechanism is of novel construction and comprises one or more magnets M' firmly secured to lugs or brackets 85 projecting from an arm 86 of frame F'. Screws 87 or other fastening devices, hold the magnets firmly in position. In the present instance I employ a pair of circular permanent magnets held together by screws or pins 88. These magnets, 50 which constitute in effect a single magnet, are provided with polar projections 89 and 90. As best shown in Fig. 10, these polar projections are separated or spaced at their free ends to form legs 89' and 90', respectively. To the spaced polar legs 89' 55 is secured a pole piece 91, and to the other polar legs 90' is attached a pole piece 92. These pole pieces are bars of soft steel or a quality of iron having high permeability. On pole pieces 91 and 92 are mounted coils 93 and 94, respectively, these coils being arranged between the pairs 60 of polar legs 89' and 90'. It is clear from Fig. 10 that the normal field flux does not pass through the coils 93 and 94, and the function of these coils is to polarize the pole pieces 91 and 92. Diaphragm 82 and armature 84 of cone 65 diaphragm D' are arranged at the opposite ends

of pole pieces 91 and 92, and in such close proximity thereto as to be readily acted upon by the variable strength of the magnetic field at the pole pieces.

The diaphragm 82 may either be of magnetic material, or it may be non-magnetic (as of aluminum or aluminum alloy) and carry a magnetic armature 82'. Instead of making the armature 82' as a separate piece of iron or soft steel, I prefer to form the same on the diaphragm by an electrolytic deposit of iron, which is held in intimate molecular contact with the body of the diaphragm, as I have attempted to indicate roughly in Fig. 13. This coating of electrolytically deposited iron need only be a thin circular plating at the center 90 of the diaphragm, so that it adds very little weight to the diaphragm and therefore does not appreciably increase its inertia.

In the operation of the diaphragms 82 and D' by the electromagnetic mechanism above described, the current variations through coils 93 and 94 at any instance affect the opposite ends of the pole pieces 91 and 92 reversely. That is to say, when the polar ends N and S are strengthened, the opposite polar ends N' and S' are simultaneously weakened, and vice versa. Consequently, the diaphragms 82 and D' are simultaneously operated slightly out of step. The practical result of this dephased operation of the diaphragms is an acoustic reproduction of rich tonal 105 quality.

To promote simplicity in the drawings, I have shown the enclosing cabinet C as a substantially rectangular box. In the practical design of such a cabinet, it is desirable to avoid sound pockets 110 by eliminating rectangular corners. I have attempted to indicate this roughly in Figs. 2, 3 and 9, where the dotted lines 95 represent panels or partitions for directing the inwardly projected sound vibrations of diaphragm D or D' out of the 115 open front of the cabinet. It is evident that the baffle board 95 by reflecting sound waves out of the cabinet amplifies the reproduction of the cone D'. In fact, the enclosed space in which the cone 120 is supported acts like an amplifying chamber of which the curved sound-reflecting board 95 forms the back wall. This chamber, therefore, increases the final tone volume and improves the quality of reproduction. These sound-reflecting panels may either be arranged within the outer walls of the 125 cabinet, or they may form part of the outer cabinet structure. The front of the cabinet is closed by an ornamental cover adapted to transmit freely the vibrations of the cone diaphragm. Such a cover, which I have indicated diagrammatically 130 by dotted lines 96 in Figs. 2, 3 and 9, may be a thin porous fabric, or a grille, or any other design of cover suitable for the purpose.

Although I have illustrated cabinet C in upright position, so that the mouth of the horn is at the 135 top, it goes without saying that the cabinet may be so designed that any of its sides may constitute the base. Therefore, when I speak of the top and bottom or front and rear of the cabinet, I use those terms in a relative sense only, and not 140 by way of restriction. The two constructions shown in the drawings are to be considered as merely illustrative examples embodying my invention, which includes various other modifications within the scope of the appended claims.

145 What I claim as my invention is:

1. A loudspeaker comprising a horn having curved portions arranged to provide a sound passage of requisite length in a comparatively small space, a cone diaphragm mounted outside of said 150

- horn in a space between the curved portions of said horn, a diaphragm connected with the inner end of said horn, and mechanism for operating both diaphragms.
5. A loudspeaker comprising a horn which consists of a main body portion having a pair of lateral branch tubes connected thereto, said branch tubes being approximately U-shaped and extending toward each other at their inner ends, a diaphragm connected to the inner end of each branch tube, a cone diaphragm mounted in the space within said branch tubes, and mechanism for operating all of said diaphragms.
3. A combined horn and cone speaker in which the cone diaphragm is supported in a space outside of said horn and bounded by portions of the horn and mechanism for operating the horn and cone diaphragm.
4. In a loudspeaker, the combination of a horn coiled back upon itself, a cone diaphragm mounted outside of said horn in the space between the coils of said horn, a diaphragm connected to the inner end of said horn and arranged adjacent to said cone diaphragm, and means outside of said horn for operating said diaphragms.
5. A loudspeaker comprising a base, a frame secured to said base, a cone diaphragm mounted on said frame, a horn supported on said base independently of said frame, said horn having a U-shaped portion arranged substantially at right angles to said frame and extending on opposite sides thereof, a diaphragm at the inner end of said horn, and means for operating said diaphragms.
35. 6. A loudspeaker cabinet containing a horn and a cone diaphragm, a frame secured in said cabinet for supporting said cone diaphragm, means independent of said frame for securing said horn in rigid position, said horn having a curved portion extending on opposite sides of said cone diaphragm, the latter being arranged outside of said horns, a small diaphragm connected with the inner end of said horn, and means for operating both diaphragms, one side of said cabinet being open for the emission of sound from said horn and cone diaphragm.
7. A combined horn and cone speaker comprising a cabinet open at the front, a cone diaphragm supported in said cabinet substantially parallel with said open front, a horn supported in said cabinet in such position that its mouth terminates at the top portion of said open front, said cone diaphragm being arranged outside of said horn, a diaphragm at the inner end of said horn, and means for operating said diaphragms.
50. 8. A combined horn and cone speaker comprising a cabinet open at one side for the emission of sound, a cone diaphragm supported in said cabinet substantially parallel with said open side, sound-reflecting walls arranged within said cabinet back of said cone diaphragm for directing sound waves into the open air, a horn supported in said cabinet and having a diaphragm at its inner end, said cone diaphragm being supported outside of said horn, and means for operating said diaphragms.
55. 9. A loudspeaker comprising a cabinet open at the front, a curved horn mounted in said cabinet, said horn having a downwardly extending front section and an upwardly extending rear section which terminates in a mouth at the top of the cabinet, a curved inner section of the horn being arranged between said front and rear sections and extending forwardly to join said front section, said horn sections forming an amplifying
- sound passage of progressively increasing area, a diaphragm at the free end of said inner section, a cone diaphragm supported in said cabinet outside of said horn between said inner and front horn sections in a position substantially parallel with the front of the cabinet, and means in said cabinet for operating said diaphragms.
10. A loudspeaker comprising a cabinet open at the front, a curved horn mounted in said cabinet, said horn consisting of a main body portion and a pair of lateral branch tubes, said main body portion having a downwardly extending front section and an upwardly extending rear section which terminates in a mouth at the top of the cabinet, said branch tubes being arranged between said front and rear sections and uniting with said front section, a pair of diaphragms connected to the free ends of said branch tubes, a cone diaphragm supported in said cabinet between said branch tubes and between the top and bottom parts of the main body portion of said horn, said cone diaphragm being positioned in a plane substantially at right angles to the plane of the main body portion of said horn, and mechanism in the cabinet for operating all of said diaphragms.
11. In loudspeaker mechanism, a pair of diaphragms supported in substantially parallel relation, a third diaphragm supported substantially at right angles to said pair of diaphragms, and means connected to all three diaphragms for simultaneously operating the same.
12. In loudspeaker mechanism, a pivoted bellcrank, and a pair of diaphragms supported substantially at right angles to each other and connected to the ends of said bellcrank, and means for vibrating said bellcrank about its pivot.
13. A loudspeaker comprising a cabinet open to the outer air, an amplifying horn mounted in said cabinet, a diaphragm for sending sound waves through said horn, a loudspeaking diaphragm supported in said cabinet independently of said horn and wholly outside thereof, and mechanism arranged between said diaphragms outside of said horn for simultaneously operating the same.
14. A loudspeaker comprising a cabinet open to the outer air, a frame rigidly supported in said cabinet, a loudspeaking diaphragm carried by said frame, a horn supported in said cabinet independently of said frame, said loud speaking diaphragm being supported outside of said horn, a diaphragm acoustically connected with said horn, and mechanism for simultaneously operating said diaphragms.
15. A loudspeaker comprising three diaphragms so constructed as to accentuate, respectively, the higher register, the middle register and the lower register of tones, one of said diaphragms being a cone diaphragm requiring no amplifier, a horn for amplifying the vibrations of the other two diaphragms, means for supporting said cone diaphragm outside of said horn, and mechanism for simultaneously operating all three diaphragms.
16. A combined horn and cone speaker in which the horn has a pair of lateral branch tubes between which the cone is mounted.
17. A combined horn and cone speaker in which the cone diaphragm is supported in a space bounded by portions of the horn, said cone diaphragm being acoustically disconnected from said horn.
18. A loudspeaker comprising a cabinet, a horn mounted in said cabinet, a diaphragm arranged

to amplify through said horn, a direct-acting diaphragm supported in said cabinet and acoustically disconnected from said horn, and actuating means for said diaphragms.

- 5 19. A loudspeaker comprising an open cabinet, an amplifying horn mounted in said cabinet, a diaphragm at the inner end of said horn, a large direct-acting diaphragm supported in said cabinet independently of said horn and open to the outer air, and actuating mechanism for said diaphragms, said cabinet also constituting an amplifying chamber for said large diaphragm.
- 10 20. A loudspeaker comprising a cabinet having an open front and a curved back wall, a horn mounted in said cabinet, a diaphragm at the inner end of said horn, a cone diaphragm supported in said cabinet independently of said horn, and actuating means for said diaphragms, said curved back wall reflecting sound waves from said cone diaphragm out of the cabinet to amplify the reproduction.

- 15 21. A loudspeaker comprising a cabinet, an amplifying horn mounted in said cabinet, a pair of diaphragms connected with said horn, said diaphragms being constructed to accentuate the higher register and the middle register of the musical scale, a cone diaphragm supported in said

cabinet and acoustically disconnected from said horn, said cone diaphragm being adapted to accentuate the lower register of the musical scale and means for simultaneously operating all three diaphragms.

80

22. A horn comprising a bell portion having inlet and outlet openings, two sound passages communicating with said inlet opening, said passages extending laterally in opposite directions approximately at right angles to a medial plane through the axis of the bell portion and curving approximately through an angle of 180° at a substantial distance from each side of the outlet opening of said bell portion.

85

23. A horn comprising a bell portion having inlet and outlet openings, two sound passages communicating with said inlet opening, said passages extending laterally in opposite directions approximately at right angles to a medial plane through the axis of the bell portion and curving through an angle of at least 180° at a substantial distance from each side of the outlet opening of said bell portion, said last mentioned bend being of such radius that said sound passages do not intersect the plane of the mouth of the bell portion.
